C. A. PARKER, JR.

AUTOMOBILE COOK STOVE

Filed Feb. 14, 1922

Inventor

C. A. Parker Jr.

Attorney

UNITED STATES PATENT OFFICE.

CHARLES A. PARKER, JR., OF COLUMBIA, TENNESSEE.

AUTOMOBILE COOKSTOVE.

Application filed February 14, 1922. Serial No. 536,417.

To all whom it may concern:

Be it known that I, CHARLES A. PARKER, Jr., a citizen of the United States, residing at Columbia, in the county of Maury and State of Tennessee, have invented certain new and useful Improvements in Automobile Cookstoves; and I do hereby declare the following to be a full, clear, and exact description of the invention, such as will enable others skilled in the art to which it appertains to make and use the same:

This invention relates to an automobile cooking stove.

One primary object is to provide a device of this nature which will utilize the exhaust products of the propelling engine of the automobile as the heating medium, so as to form an especially useful accessory for tourists and campers using the automobile.

Another important object is to provide a device of this character which may be detachably applied to an automobile, as at the running board, which is capable of disassembly and arrangement of its parts into compact form for portage, which may have a novel fire box section and a novel oven section cooperating therewith and selectively applicable thereto, and otherwise to provide a construction embodying the details, combinations and arrangements of the parts as illustrated in one practical embodiment in the accompanying drawing.

In said drawings:—

Figure 1 is a fragmentary side elevation of an automobile, showing my improved cooking stove attachment in operative position, and partly in section;

Figure 2 is a longitudinal sectional view through the stove proper;

Figure 3 is a cross sectional view through the entire device on the plane of line 3—3 of Figure 2;

Figure 4 is a side elevation of the stove in detached and portable form;

Figure 5 shows the stove in front end elevation and in place on a running board, the latter being shown fragmentarily;

Figure 6 is a detail sectional view on the line 6—6 of Figure 5, and

Figure 7 is a detail sectional view of the upper corner of the fire box illustrating the means to hold the parts thereof in rigid relation.

Like reference characters designate like or similar parts in the different views.

An automobile or self propelled vehicle

has been conventionally shown in Figure 1 as at A of which the step or running board at one side is designated B, the propelling engine thereof C, and pipe for exhaust products of combustion at D. The stove may have a fire box generally designated E and adapted to removably rest on the running board B. This fire box has an inner rectangular closed hollow section 10 which is disposed within an outer section 11, open at its top so that the top wall 12 will be exposed and may serve as the hot plate. To prevent improper radiation of heat to the running board and to confine it to the hot plate 12, a lining as of asbestos or other heat insulating material designated 13 is provided intermediate the shells 10 and 11. As shown in Figure 3 and Figure 7, the shell 11 may have an inwardly extending flange 14 at each side adapted to overlap an outwardly projecting rib 15 on the shell 10 to secure the shells 10 and 11 against detachment.

A union or coupling 16 is provided in the exhaust pipe B and a conduit or pipe 17 leads therefrom to the interior of the fire box 10. Operable within the union 16 is a suitable valve 18, pivoted at 19, and adapted for manual operation to open or close the exhaust pipe D in the rear of pipe 17, to respectively permit the products of combustion to escape to the atmosphere as usual or to deflect them through the pipe 17 into the shell 10. Pipe 17 is preferably detachable from pipe D and section 10 as at elbows 20 and 21 forming a slip or stove pipe joint therewith.

At the same end of the fire box E as the pipe 17, an outlet pipe 22 leads therefrom, preferably being detachably connected thereto by means of a slit or stove pipe elbow joint at 23. Said pipe is substantially of U-shape in that its outlet end is deflected to fit over the outer longitudinal edge of running board B and then extend inwardly under the same to direct the products escaping therefrom away from the vicinity of the stove.

Within the shell 10, a baffle plate 24 may be provided extending from the right hand end wall thereof in Figures 1 and 2 and terminating short of the left hand end wall, thus insuring a tortuous passage of the exhaust products through the shell to more efficiently heat the same before escape through the pipe 22.

The fire box E is adapted to be detachably

fastened to the running board B in any suitable manner and for instance by means of clamps having brackets 25 adapted at one end for removable insertion into recesses or sockets 26 in the shell 11, as best shown in Figure 3 and having screws 27 operable against the under surface of the running board. Preferably a plurality of the clamps or brackets are provided.

10 A cover or oven section is preferably provided at 28 being of hood shape, open at the bottom, and of such height that its top wall is spaced a distance above the hot plate 12 to thus form an oven space. Said hood 28 is adapted to slide or be placed over the fire box E and to facilitate such movement, one end wall of the hood 28 is provided with slots as at 29 so that the pipes 17 and 23 will not interfere with such movement. In addition, one side is notched or cut away as at 30 so that the brackets 25 will not interfere with such movement.

A suitable means is preferably provided whereby the hood 28 may be positively but 25 detachably connected to the fire box section. To this end, latches 31, of any suitable number, and preferably of resilient or spring material are secured by rivets or other means 32 at the ends of the hood 28. These 30 latches have manipulating knobs 33 and keepers or lugs 34 adapted for projection through slots 35 in the end walls of hood 28 and into notches or recesses 36 in the end walls of the shell 11. By manipulation of 35 the knob 33, the latches may be swung outwardly to disengage the keepers 34 from recesses 36 to thereby detach the hood 28. Latches 31 normally assume the locked position shown in Figure 6.

40 In use, the device in the assembled form of Figs. 2 and 4 with the hood 28 latched to the fire box E, is adapted to be carried in the automobile, handling thereof being facilitated by a suitable handle as at 37. While 45 the engine of the automobile is operating to propel the same, the valve 18 is in position closing the pipe 17 and thus causing the exhaust gases from the engine C to escape into the atmosphere as usual.

50 When the stove is to be used, the section E is disposed on the running board as shown in Figure 1 and the clamp or bracket 25 applied. The pipes 17 and 22 are thereupon connected and valves 18 moved to the position of Figure 1 where the products from the exhaust pipe D will pass through the pipe 17 and through the shell 10, thus effectively heating the hot plate 12 and escaping through the pipe 22 into the atmosphere.

60 The articles to be cooked may be placed directly on the hot plate 12 and in the case of baking or of maintaining food in a warm condition, the hood 28 is preferably applied

over the fire box, being fastened in place by the latches at 31.

65 It will be realized that when the device is in a folded condition as in Figures 2 and 4, the pipes 22 and 17 may be carried within the same, and in addition, a number of cooking utensils or other articles may be also 70 be accommodated therein. As merely one practical embodiment has been illustrated and described, it is to be understood that changes in the details may be resorted to provided they fall within the spirit and 75 scope of the invention.

Having thus described the invention, what I claim is:

1. A stove of the class described having an outer shell for disposition on the running 80 board of an automobile, an inner shell adapted to be received within the outer shell and have its upper surface flush with the upper edges of the outer shell, heat insulating material between the adjacent surfaces 85 of the shells, the upper surface of the inner shell forming a hot plate, a baffle within the inner shell and contacting with the upper and lower walls thereof and running from one end thereof to within a short distance of 90 the other end thereof, means adapted to connect the exhaust pipe of an automobile engine to the inner shell at one side of the baffle, means to connect an outlet pipe to the inner shell at the outer side of the baffle, 95 means to connect the outer shell to the running board of an automobile, a hood for said stove, said hood having its top wall spaced from the upper side of the hot plate and forming an oven when the stove is in use 100 and forming a storage space when the stove is not in use, and means carried by the hood and engaging the outer shell and detachably securing the hood to the shell, whereby the stove is formed into a compact and easily 105 handled structure when detached from the running board.

2. A stove of the class described having an outer shell for disposition on the running board of an automobile, an inner shell within 110 said outer shell and having a surface adapted to form a hot plate, said inner shell being hollow and adapted to be connected to the exhaust pipe of the automobile engine, a hood adapted to fit over the hot plate to 115 form an oven, insulating material spacing the inner shell from the outer shell, and overlapping means carried by the shells within the insulating material and serving to prevent detachment of the shells.

120 In testimony whereof I affix my signature in presence of two witnesses.
